(57) **CLAIM**

The ornamental design for a display screen or portion thereof with graphical user interface, as shown and described.

DESCRIPTION

FIG. 1 is a first embodiment of a front view of a display screen or portion thereof with graphical user interface; and, FIG. 2 is a second embodiment of a front view of a display screen or portion thereof with graphical user interface.

The outermost broken lines in the figures show a display screen or portion thereof and form no part of the claimed design. The other broken lines in the figures show portions of the graphical user interface that form no part of the claimed design.

The solid black surface shading and stippled portions of the display screen in FIG. 1 indicate a color contrast in appearance. The solid black surface shading of FIG. 2 indicates a color contrast in appearance.
